UNITED STATES PATENT OFFICE

OSCAR V. GREENE, OF CLEVELAND, OHIO

SELF CLEANING FILTER

Application filed May 4, 1929. Serial No. 380,412.

The present invention relates to air or dust filters particularly adapted for use in connection with the filtering of air for buildings and the like, and more particularly provides a filter mechanism which may be readily cleaned without removing it from the installation, the cleaning means being built in as a portion of the filter. To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:

- 20 Fig. 1 is a front elevational view of the filter; Fig. 2 is a side elevational view of the same; Fig. 3 is a cross-sectional view on the line 3—3 of Fig. 1; Fig. 4 is a sectional view through one of the filtering sheets; Fig. 5
25 is a front elevational view of a unit heater showing a modified form; Fig. 6 is an end view of the unit shown in Fig. 5 taken on the line 6—6 thereof; and Fig. 7 is a section of a detail.
- 30 In the present type of filter there is provided a main frame 1 which has a closed-in portion 2 at the top, in which is mounted a roller 3 having its ends journaled in the side frame members, and which is likewise provided at the bottom with a casing 4, in which a second roller 5 is mounted, this roller being mounted in slots 6 so as to be vertically movable and being of sufficient weight to maintain the filter belts 7 and 8 under the desired
35 tension. The framework has a protecting sheet 9 of heavy mesh wire screen mounted in front of the two belts 7 and 8 of filtering material. Each belt consists of a sheet 10 of relatively coarse mesh flexible wire screen
40 and a sheet 11 of filter cloth, these sheets being bound together to form a flexible unit with minimum stretch but with strength to resist wear and tear incident to operation. The two belts are in contact where passing
45 over the rollers but are spaced apart through

the main portion of the filter casing by means of spacing rolls 15, the inner belt 8 passing over the inner sides of the rolls and being thus spaced from each other and from the outer belts and being held under tension, the rollers being carried by end brackets 51 which are pivotally mounted in the frame and which are held by a spring 52 connecting the bracket arm 53 and the frame. The space between belts is widest at the vertical center of the filter and the belts approach each other as they near the top and bottom where they pass over the main rolls. In operation the belts are held stationary until they have accumulated enough dust and dirt to make cleaning desirable.

As filters of this type are commonly used only during the daytime in building installations, they may be easily cleaned at night when the ventilating fans are shut down. 70 The cleaning mechanism is built into the lower portion of the casing as an integral unit, this cleaning mechanism consisting, as shown, of a pair of vacuum cleaning nozzles 16 and 17 formed in the front of the casing 4 and substantially covering the full width of the filter. These two nozzles are connected together by a pipe 18 having a single outlet 19, to which may be attached the usual vacuum hose connection or vacuum cleaning connection of any type. When it is desired to clean the filter, the vacuum hose is attached to the connection and then the belts are rotated so as to pass the outer surface of the belt over the vacuum cleaner nozzles thus sucking the dirt back from the filter belts into the vacuum cleaner. The usual procedure is to move the belt around so that the sides of the two belts, which are normally at the rear of the filter, are reversed and are left as the first two or front two belts of the filter, although of course the belts can be completely cleaned, if this is desired.

To rotate the belts, the lower filter casing is provided with a platform 20 on which is mounted a motor 21 and a speed reducing mechanism 22, this mechanism driving a shaft 23 which extends along the rear of the lower filter casing 4, this shaft having a sprocket 24 on its outer end, preferably chain 100

connected to a sprocket 25 which is carried on an extension of the lower roller 5. At the other end the motor carries a pulley 26 which is preferably belt-connected to a beater roll 27 which is mounted in the front of the casing in substantial contact with the filter belts, this roll being provided with longitudinal projections, brushes or ribs 28 which beat against and jar the belts as they are rotated. The beater roll is driven at high speed, whereas the lower, belt roller 5 is driven at a very slow speed through the reduction gearing and the further speed reduction obtained from its belt drive. It is thus possible to move the belts around and past the beater roll and the suction nozzles very slowly so that the dust and dirt which accumulates on the filter belts is jarred loose and sucked out and discharged in any desired manner.

As illustrated in Fig. 7 the belt 7 passes over a curved plate 62 along the top of the lower casing while the inner belt passes over an idler roller 63, the belts being in contact with each other and being held to prevent vibration above this horizontal line. The beater roll jars the belts 7 and 8 between the idler rolls and the pressure line where the belt passes between the casing and the main roll 5, there being a sealing strip 64 mounted on the casing at this line to limit the vibration of the belts to this area defined by the idler roll 63 and strip 64 which is substantially the size of the vacuum cleaning nozzle opening 65 in the casing 4. The cleaning action is thus confined to the nozzle area and vibration of the belts above such area, and consequent dislodging of dust and dirt is prevented.

In Figs. 5 and 6 the same type of mechanism is applied to a unit heater, which consists of a small casing 30 having a heating coil 31 near the top, outlet openings 32, a blower fan 33 and bottom inlet openings 34 which are controlled by a damper 35, the filter inlet 36 being placed between the blower mechanism 33 and the bottom openings 34, and here the filter unit, because of the limited static capacities of the fans employed, consists preferably of a single belt 40 similar in construction to the belts previously described, this belt being mounted in a frame carrying two rollers 41 and 42, one of which, 42, is spring-pressed outwardly to obtain the desired belt tension. At one end of the casing a vacuum cleaner nozzle 44 is mounted to extend across and co-operate with the belt, this nozzle being provided with a suitable connection 45 which communicates with the outside of the casing, to which may be easily attached the vacuum hose connection. To rotate the belt when it is desired to clean the same, the roll 41 at the vacuum cleaner end of the casing has one end 47 exposed through the casing, to which is attached a crank 48 so that the roll may be

slowly rotated by hand, thus passing the belt across the vacuum cleaning nozzle at any desired speed, and the belt will be rotated by hand until thoroughly cleaned. To accomplish this, the ventilating mechanism, consisting of the blower fan for the unit heater, is of course shut down while the vacuum cleaning is being accomplished. In both forms above described, the filter elements and supporting frames are sealed to prevent any by-passing of dirty air around the filter and direct the air flow through the several spaced elements in sequence.

The present type of filter is particularly adapted for use where vacuum cleaning means are available and where it is desirable to make a permanent installation as the cleaning of the filter is automatically accomplished, the cleaning mechanism being built as an integral part of the filter mechanism itself. By the use of flexible belts, the desirable belt spacing, that is, the spacing between individual filter elements, is easily accomplished and the cleaning is satisfactory as the outer belt on the front side of the filter is that portion which collects the greatest amount of lint and dust, and this is the belt, or portion of the belt, which is directly in contact with the cleaning nozzle, and thus the dirt and dust is easily and quickly removed.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a filter, the combination of a frame, having spaced rolls, an endless filter belt mounted in said frame over said rolls, a casing at one end of said frame, and having a vacuum cleaning nozzle opening adjacent the belt, means for holding the belt against said casing at the top and bottom of said nozzle opening, other means in said casing for jarring said screen at said opening, and means for moving said belt past said opening.

2. In a filter, the combination of a frame, having spaced rolls, an endless filter belt mounted in said frame over said rolls, a casing at one end of said frame, and having a vacuum cleaning nozzle opening adjacent the belt, means for holding the belt against said casing at the top and bottom of said nozzle opening, a beater roll mounted in said casing across said opening, means for rotating said beater roll to vibrate said belt at said opening, and means for moving said belt past said opening.

3. In filter construction, the combination of a frame, a roller mounted at each end of

said frame, two belts of filter material extending around said rollers, said belts being continuous and in superposed relation, and means intermediate of said rollers and adapted to engage the inner one of said belts to space the inner belt away from the other belt, and to space the portions of the inner belt between the rollers from each other.

4. In filter construction, the combination of a frame, a roller mounted at each end of said frame, two belts of filter material extending around said rollers, said belts being continuous and in superposed relation, and a pair of rollers mounted in said frame at approximately equal distances from said first rollers and adapted to have the inner of said two belts pass over and in contact with the inner surfaces of the rollers to space the inner belt from the outer belt, and to space the longitudinal portions of the inner belt from each other.

5. In a filter, the combination of a frame, having spaced rolls, two endless filter belts mounted in superposed relation in said frame over said rolls, a casing at one end of said frame having a vacuum cleaning nozzle opening adjacent said belts, means for holding said belts against said casing at the top and bottom of said nozzle opening, other means in said casing for jarring said screens at said opening, and means for moving said belts past said opening.

6. In a filter, the combination of a frame, having spaced rolls, two endless filter belts mounted in superposed relation in said frame over said rolls, a casing at one end of said frame having a vacuum cleaning nozzle opening adjacent said belts, means for holding said belts against said casing at the top and bottom of said nozzle opening, a beater roll mounted in said casing across said opening, means for rotating said beater roll to vibrate said belts at said opening, and means for moving said belts past said opening.

45 Signed by me this 3d day of May, 1929.
OSCAR V. GREENE.
